UNITED STATES PATENT OFFICE.

ARTHUR E. SMITH, OF GENEVA, PENNSYLVANIA.

MATCH-BOX.

SPECIFICATION forming part of Letters Patent No. 791,222, dated May 30, 1905.

Application filed November 17, 1904. Serial No. 233,151.

To all whom it may concern:

Be it known that I, ARTHUR E. SMITH, a citizen of the United States of America, residing at Geneva, in the county of Crawford and State of Pennsylvania, have invented certain new and useful Improvements in Match-Boxes, of which the following is a specification, reference being had therein to the accompanying drawings.

10 This invention relates to certain new and useful improvements in match-boxes; and it relates more particularly to that type of box which is designed to deliver but one match at a time.

15 The primary object of the invention is to provide a device of the above character which will be of an inexpensive construction and which will effectually insure the delivery of a match at each operation and which will also 20 effectually insure the prevention of more than one match being delivered with each operation.

Briefly described, the invention comprises a receptacle or container that is preferably 25 provided with a hinged lid in order that the matches may be readily placed therein. Within the receptacle or container is a partition extending at an incline across the same and which to a certain extent forms a bottom 30 upon which the matches rest and also to a certain extent acts as a slide down which the matches fall to be delivered. The box is provided in its front wall with a spring or hinged door which swings inwardly only, and this 35 door carries arms which when the door is forced inwardly engage with angular ends formed on a rock-shaft that is journaled in the bottom of the receptacle or container. This rock-shaft carries curved fingers which 40 operate in the slots provided therefor in the lower end of the partition and which fingers when the door is forced inwardly are elevated into engagement with the matches, whereby to cause the match retained by the 45 pocket—it being the lowermost match of the pile of matches in the container—to be discharged, the door having entered the container past the location of the pocket contained in the false bottom, thus allowing free 50 passage and delivery of a single match on a

tray provided on the extreme lower end of said partition-wall.

In describing the invention in detail reference will be had to the accompanying drawings, forming a part of this application, 55 wherein like reference characters designate corresponding parts throughout the several views, in which—

Figure 1 is a front elevation of a match-box constructed in accordance with my invention. Fig. 2 is a transverse vertical sectional view thereof, taken on the line *x* *x* of Fig. 1. Fig. 3 is a horizontal sectional view taken on the line *z* *z* of Fig. 2, and Fig. 4 is a like sectional view taken on the line *y* *y* of 65 Fig. 2.

The receptacle or container A comprises a back B, a top C, which is preferably hinged, a bottom D, and a front wall comprising a stationary upper part E and a swinging door F. 70 The swinging door F forms a part of the front wall, and this swinging door is adapted to be swung inwardly of the container only. The outward movement of the swinging door may be limited by any desired means, preferably by employing a hinge G, which will permit the door to swing inwardly, but will limit its outward movement, so as to arrest the same when it is in alinement with the stationary upper section E. On the stationary 80 upper section E or at any other desired point may be provided a friction-surface H. In the receptacle or container and extending across the same at an incline or angle is a false bottom or partition J, which meets with 85 and is secured to the back B, its lower edge extending through an opening in the bottom near the front and extending out beyond the front of the box or container and terminating in the match-receiving tray K. This partition or false bottom J where it extends through the bottom of the receptacle or container is curved to form a pocket, and this curved portion is provided with one or more slots L, in which work curved fingers M, that are secured upon a shaft N, journaled in the base 90 D of the receptacle or container. This shaft N has its ends O bent upwardly to form arms which are adapted to be engaged by the angular ends P of arms R, carried by the 100

door, when said door is swung inwardly of the box or container. In practice I have generally employed a rod or strip of material S, which I firmly affix to the front of the door 5 F, as shown in Fig. 1, bending the ends down outside of the box or container to form arms R. I also generally shape this rod or strip as shown at T in order to indicate the proper position for exerting pressure against the 10 door to move the same inwardly of the container.

In operation it will be observed that when pressure is exerted at point T on the door and the same is moved inwardly of the container 15 the ends P will engage with arms O, causing the rock-shaft N to be actuated and moving the arms M upwardly against the pile of matches and permitting the lowermost match to roll down over the curved 20 face V of the arms M through the passage-way, which now extends below the lower edge of the door, and out onto the tray K. The moment that pressure is relieved from the spring or hinged door by its own volition 25 it returns to its normal or closed position.

It will be noted that various changes will be made in the details of construction without departing from the general spirit and scope of the invention.

Having fully described my invention, what I claim, and desire to secure by Letters Patent, is—

1. A container or receptacle having a partition terminating at its lower end in a match-receiving tray lying beyond the front of the 35 container, a swinging door forming a part of

the front wall of the container, a rock-shaft journaled in the bottom of the container and having upwardly-extending arms, and arms carried by the swinging door to engage the 40 arms of the rock-shaft, as and for the purpose described.

2. A match-box comprising a container having a partition forming a false bottom, and terminating at its lower end in a match-receiving tray, a swinging door forming a part of the front wall of the container, a rock-shaft journaled in the bottom of the container and having upwardly-extending arms, delivery-fingers carried by the rock-shaft and operating in slots in the partition, and arms carried by the swinging door to engage the arms of the rock-shaft and actuate the delivery-fingers, substantially as described. 55

3. A match-box comprising a container having a partition provided near its lower end, a rock-shaft journaled in the base of the container and provided with delivery-fingers operating in the slots of the partition, a swinging door forming a part of the front wall of the container, and means carried by the door for operating the rock-shaft and thereby operating the delivery-fingers, substantially as described. 60

In testimony whereof I affix my signature in the presence of two witnesses.

ARTHUR E. SMITH.
